FILLER FOR GREASE GUNS

Tilphare Clemenson, Grafton, N. Dak.

Application September 14, 1935, Serial No. 40,651

1 Claim. (Cl. 221—47.5)

This invention aims to provide a novel device for holding grease and the like, of the kind usually employed in connection with grease guns. The invention aims to provide novel means whereby the grease may be forced out of the receptacle, into a grease gun, it being possible to eject practically all of the grease, and there being little or none of the grease left in the receptacle. The invention aims to provide novel means for constructing and reenforcing the lower end of the receptacle. A further object of the invention is to provide a device of the class described so constructed that one of them may be stacked readily on top of another, without danger of having the superposed receptacle slip laterally or fall down.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Fig. 1 shows in longitudinal section, a device constructed in accordance with the invention, parts being in elevation;

Fig. 2 is a top plan;

Fig. 3 is a transverse section on the line 3—3 of Fig. 1;

Fig. 4 is a section on the line 4—4 of Fig. 3.

The device forming the subject matter of this application comprises a receptacle, made of any suitable material, preferably sheet metal. The receptacle embodies a tubular or cylindrical body 1, provided adjacent to its lower end with an inwardly projecting, annular, horizontal shoulder 2, terminating in a depending tubular neck 3, of less diameter than the body 1. Within the body 1, and secured in place, is a bottom 4. The constituent material of the bottom 4 preferably is somewhat thicker than the material out of which the body 1 is made. The bottom 4 has a depending annular flange 5, fitting closely within the smooth lower portion of the body 1. At its lower edge, the flange 5 is supplied with an inwardly projecting annular shoulder 6, resting on the shoulder 2 of the body 1. The shoulder 6 is supplied with a depending neck 7, fitting closely within the neck 3 of the body 1. The bottom 4 is

provided with a depressed trough 8, extending from a point near to the center of the bottom, to the periphery of the bottom. The inner end of the trough 8 may be inclined, as shown at 16. The body 2 is supplied with an opening 9, located at the outer end of the trough 8, and communicating therewith. A horizontal spout 10, or any other kind of a spout, is secured to the outer surface of the body 1, about the opening 9 in the body.

The body 1 is corrugated to form a continuous and spiral thread 11, extending downwardly from the extreme upper edge of the body to the bottom 4. The numeral 12 designates a disk-like top, having an upstanding annular rim 14, which is engaged with the spiral thread 11 of the body 1. A transverse handle 15 is secured to the top 12.

In practical operation, the body 1 is filled with grease or any other lubricant, indicated at 17, and the top 12 is threaded into the body 1, as shown in Fig. 1. When the occasion for the use of the device arises, the top 12 is threaded downwardly in the body 1, and the grease, led by the trough 8, passes through the opening 9 of the body, into the spout 10, and from the spout into the grease gun to be filled. The top 12 may be threaded downwardly until the top rests on the bottom 4, and practically all of the grease in the receptacle can be forced out.

The parts 1, 3, 5, 6 and 2 reinforce the receptacle at its bottom, and give an unusually strong construction.

The external diameter of the tubular neck 3 of the body 1 is slightly less, or approximately equal to, the internal diameter of the upstanding rim 14 of the top 12. Consequently, the neck 3 of one receptacle may be placed within the rim 14 of another receptacle, and in this way, the devices may be stacked up to any reasonable height, without danger that they will slip laterally on each other and fall down.

The device forming the subject matter of this application is simple in construction, but will be found thoroughly effective for the ends in view.

Having thus described the invention, what is claimed is:

In a device of the class described, a receptacle including a tubular body provided with an outlet, a bottom in the body and having a depressed trough leading to the outlet, the body having a continuous thread leading from the extreme upper edge of the body to the bottom, a top having a plain, flat lower surface shaped to fit against the entire upper surface of the bottom saving where the trough exists, the top having an up-

standing rim which is engaged throughout its entire height with the thread when the upper edge of the rim is flush with the upper edge of the body and when the top is engaged with the 5 bottom, an upstanding handle on the top, the body having a reduced neck at its lower end, the neck being receivable within the rim of the top

of a like receptacle, to facilitate stacking, the height of the neck being at least equal to the height of the handle, to avoid contact between the handle of a lower receptacle and the trough of an upper receptacle, thereby to avoid consequent instability in stacking. 5
